UNITED STATES PATENT OFFICE.

HENRY LINES, OF NEW HAVEN, CONNECTICUT.

IMPROVEMENT IN LANDAU-CARRIAGE TOPS.

Specification forming part of Letters Patent No. 174,372, dated March 7, 1876; application filed January 31, 1876.

To all whom it may concern:

Be it known that I, HENRY LINES, of New Haven, in the county of New Haven and State of Connecticut, have invented certain new and useful Improvements in Landau Carriages; and I do hereby declare that the following is a full, clear, and exact description thereof, which will enable others skilled in the art to which it pertains to make and use the same, reference being had to the accompanying drawings, and to the letters of reference marked thereon, which form a part of this specification, in which drawings—

Figure 1 is a side elevation, with the top closed, showing by dotted lines the position of the springs. Fig. 2 is a top view, with the front hood folded down, showing the springs and connecting-rods. Fig. 3 is a transverse section, showing the inner face of the front pillars, with the springs and rods adjusted in recesses in the pillars. Fig. 4 is a side view of the front part of the top, folded down, with side of front pillar and top rail broken off, showing the position of the springs and rods.

My invention relates to landau carriages having glass windows in the front and sides of the front hood; and it consists of springs, adjusted in recesses in the front pillars and top rails of the front hood, for balancing the front top in folding and raising the same, as hereinafter fully described.

A is the body of the carriage, and B represents the front pillars of the top, which pillars are provided with recesses *a a*, in which spiral springs *b b* are adjusted on rods *c c*, the upper ends of which are provided with screws and nuts, forming the bearings of the upper ends of the spiral springs, and the lower ends of the rods are pivoted to lugs *d d* on the hinges *e*, connecting the pillars with the body of the carriage. These springs and rods are inclosed in the recesses in the pillars by plates *a' a'*, so that they occupy no space in the carriage and

are entirely out of the way. C represents a flat steel spring, adjusted in a recess in the top rail D of the front hood, and is connected with a rod, *b'*, pivoted to lugs *c'* on a plate, *d'*, in a recess in the upper part of the front door-post E. In constructing the tops to be operated by the flat springs each top rail D and D' is provided with a similar spring.

The spiral springs are contracted and the flat spring bent downward when the top is folded down, as shown in Fig. 4, in which position the force of the springs bears the top upward, preventing it from falling and injuring the parts or breaking the glass in folding, and aiding in raising the top to its upright position.

Either the spiral springs or the flat springs may be used alone without the others, or, to secure greater force, both kinds may be used, as shown. And the lugs *d d* may be made, and attached to the posts, separate from the hinges.

What I claim as new, and desire to secure by Letters Patent, in a folding-top carriage, is—

1. The spiral springs *b*, adjusted in recesses in the front pillars B, in combination with rods *c*, hinged or pivoted to the body of the carriage, substantially as and for the purposes described.

2. The flat spring C, adjusted in a recess in the top rail D, in combination with a rod, *b'*, pivoted or hinged to the upper part of the front door-post E, substantially as and for the purposes described.

In testimony that I claim the foregoing as my own invention, I affix my signature in presence of two witnesses.

HENRY LINES.
